United States Patent

Des. 236,783
Patented Sept. 16, 1975

236,783

EXHIBIT DISPLAY APPARATUS

William E. Muempfer, South Bend, Ind., assignor to
Exhibitech, Inc., South Bend, Ind.

Filed July 14, 1972, Ser. No. 271,823

Term of patent 14 years

Int. Cl. D20—02

U.S. Cl. D6—168

Fig. 1

Fig. 2

Fig. 3

Fig. 4FIG. 1 is a perspective view of an exhibit display apparatus embodying the present invention showing the apparatus in its closed and shipping condition;

FIG. 2 is a horizontal cross-sectional view taken on line 2—2 of FIG. 1;

FIG. 3 is a perspective view of the present exhibit display apparatus showing it in one of its open arrangements for an exhibit display; and

FIG. 4 is a perspective view of the exhibit display apparatus showing another open arrangement for an exhibit display.

The sections may be connected by hinge means to one another as illustrated in several of the views.

I claim:

The ornamental design for an exhibit display apparatus, substantially as shown and described.
